United States Patent Office.

T. W. KENNEDY, OF AVON, ILLINOIS, ASSIGNOR TO HIMSELF AND
THATCHER NICKERSON, OF SAME PLACE.

Letters Patent No. 72,503, dated December 24, 1867.

IMPROVEMENT IN HAND-TRUCKS FOR MOVING BARRELS, &c.

The Schedule referred to in these Letters Patent and making part of the same.

TO ALL WHOM IT MAY CONCERN:

Be it known that I, T. W. KENNEDY, of Avon, in the county of Fulton, and State of Illinois, have invented a new and improved Hand-Truck for Moving Barrels; and I do hereby declare that the following is a full, clear, and exact description thereof, which will enable those skilled in the art to make and use the same, reference being had to the accompanying drawings, forming part of this specification, in which—

Figure 1 represents my improved truck for moving a barrel in an upright position, as shown in red.

Figure 2 is a view of one part detached.

Similar letters of reference indicate corresponding parts.

This invention relates to a new and useful improvement in the construction of a hand-truck for moving barrels about from place to place in an upright position.

The improvement consists in connecting with the handles of the truck jointed hooks or grapples, for catching over the chine of a barrel, to hold it steadily in an upright position on a truck, when moved.

A represents the body of a hand-truck mounted on rollers at the lower end, and in general construction similar to an ordinary hand-truck, with a curved form to fit a barrel lengthwise, and a foot-piece, *a*, to lift and support the lower end of a barrel. On the upper end of the truck are fastened standards *b b*, on the rear side to the side rails *c c*, on the ends of which standards are pin-jointed bent-lever handles *d d*, connected by a cross-brace, *e*, at the outer ends of the long arms of the levers. Hooks or grapples *h h* are connected with the short arms of the levers *d d*, working on a pin in slots in the arms, and pivoted on the upper ends of the side rails *c c* of the truck. When a barrel is taken upon the truck, the hooks *h h* catch over the chine of the barrel, and hold fast by bearing upon the lever-handles *d d*, as shown in the drawing, and thus a barrel may be moved about in an upright position, and carried around a counter, and to places not accessible with ordinary trucks.

Having described my invention, I claim as new, and desire to secure by Letters Patent—

The bent-lever handles *d d* and the hooks *h h*, in combination with the truck A, constructed and operating substantially as and for the purpose herein described.

T. W. KENNEDY.
